COMB

This invention relates to combs and to an improvement in the construction and manufacture of the comb described in U.S. Pat. No. 1,886,357 to Rugaber.

The Rugaber comb had definite advantages of design but it was breakable and was made with sawn teeth: after the blank had been molded in the solid it was saw cut to produce the teeth. The teeth projected directly from the back and had parallel faces. Sharp edges and points were left by the saw, making smoothing operations necessary. The rough faces left by the saw at the base of the teeth were points of weakness leading to loss of teeth or breaking of the back. Shaping of the teeth to assist the stroke to liven the hair during combing was not practicable.

It is an object of this invention to make a comb on the Rugaber design, stronger, more durable, with no cut surfaces, with teeth shaped for strength and to assist in gathering and livening locks of hair, and which is unbreakable for all practical purposes in the uses for which it is intended.

The objects of the invention are accomplished by a comb of new structural design, which has no raw or rough surfaces, which is far stronger than the Rugaber comb, all parts of which are efficiently coordinated and interrelated for efficiency and durability. This has been accomplished by a comb having a back extending from one corner of the comb diagonally to the other corner, the center portion of the back having teeth projecting in both directions and the end portions having teeth projecting oppositely in one direction, ribs of cross section smaller than the back extending along the back at the bases of the teeth, the teeth being integral extensions of the ribs. In making the comb the preferred process is by injection molding and the preferred materials are polystyrene or polypropylene. The problem of composition arose because of the large number of rejections of combs for imperfection which occurred during the manufacturing process when using rubber or organic plastics normally successful in coarse injection molding operations, but which could not satisfy the requirement that every part and line of the comb must be fully formed and perfect in the mold.

The new comb involves a girder construction of back which makes it lighter and stronger, and a tooth and back construction which greatly strengthens the comb at the line of attachment of the back and the teeth. The teeth are of elongated diamond shape with rounded points and leading and following edges, providing a gap between adjacent teeth which compresses the hair as it is drawn toward the short axes of the diamonds and then releases it as it passes therebeyond, gathering the hair in strands and increasing the effectiveness of the stroke and the livening effect on the hair. There is also novelty in the proportions of the parts.

The accompanying drawings illustrate the preferred model of the novel comb:

FIG. 1 is a side elevation of a full scale model;

FIG. 2 is a section on line A-A of FIG. 1;

FIG. 3 is a section on line C-C of FIG. 1;

FIG. 4 is a section on line B-B of FIG. 3 showing the cross section of the coarse teeth; and

FIG. 5 is a section on a line equivalent to B-B through a fine tooth.

Referring now to the numbers of the drawings the back 10 of the comb extends diagonally through the teeth which project outwardly from it in opposite directions, the fine teeth projecting from one end and the central portion of the back and the coarse teeth projecting from the other end and the central portion of the back. The back terminates in studs 11, 11' which have inner faces parallel to the teeth. The cross section of the back is shown in FIG. 2 as an elongated oval having a long and a short axis, the general conformation of which is convex. Concave grooves or flutings 12, 12 extend along that portion of the back from which extend the teeth. The central part of the back in its preferred form thus has an equal number of alternating convex and concave portions. This is a girder structure which reduces the weight of the comb and increases its strength. This structure provides what is in effect a project-

ing rib 13 at the end of each long axis of the back, the teeth being developed out of the ribs.

The coarse teeth 14 and the fine teeth 15 are developed out of the ribs 13 and preferably not out of the central convex part of the back. The teeth are of elongated, diamond shape having a long axis X and a short axis Y. The ends of the diamonds on the long axis are truncated and curved as at 16. The arc of a circle is a satisfactory form for the tooth edge but other smooth shapes can be adopted. This tooth shape provides a relatively wide gap for the gathering of locks of hair, and a narrower passage midway between the edges of the teeth, a structure which adds efficiency to the combing stroke as it gently compresses and releases the locks of hair, increasing the livening effect of the stroke. The ends of the teeth are rounded as indicated in FIG. 3 so that no portion of the comb presents harsh lines or broken surfaces.

The back of the comb at the ends, as indicated in FIG. 3, has only one pair of flutings, the back being finished opposite to

20 the teeth in any convenient way such as a spade shape. The construction of the back as described allows sufficient flexibility without permitting excessive bending. This may be understood in that a very flexible comb will bend until too much effort is required to draw it through the hair. The reverse curvature of convex and concave surfaces establishes a resistance which is practically ideal and which is largely determined by the spacing of the teeth.

In a preferred form of the invention there may be 36 coarse teeth of .054 inches short axis, and 37 spaces of .046 inches in 30 a total space of 3.646 inches. For fine teeth there may be 58 teeth of .034 inches and 59 spaces of .028 inches in a total length of 3.624 inches.

The teeth are extensions of the ribs 13 and do not enter, or 35 enter only partially, the flutings which extend above the upper ends of the teeth along the back, it being deemed advisable to leave the flutings at least partly free.

The comb is preferably made by injection molding but not all compositions are useful for this purpose. The teeth are fine, 40 their surfaces must be fully developed, and of polished aspect. They must be strong and not subject to breaking by any normal use. To accomplish this with what could be called normal injection molding compositions is not practical, as the loss of combs from imperfect molding is too extensive. As a consequence, a particular composition, or rather a particular class of compositions, has been employed in this use.

The exposed parts of the ribs between the teeth are 45 preferably curvilinear, usually on a circular radius, which not only aids in livening the hair but contributes to the perfection of the teeth during molding. The ribs are usually to be of less thickness than the body of the back but thicker than the grooves or flutings.

In combing the hair the teeth select a lock as wide as the 50 space between the leading edges of the teeth, the locks are compressed mildly as they progress and are gradually released after they pass the short axes of the teeth, a stroking action which serves to draw oils into the hair from the scalp and to add luster. There are no notches or surfaces to catch the hair and snarl it. The comb is of superior design and efficiency and it is readily made by injection molding.

As many apparently widely different embodiments of the present invention may be made without departing from the spirit and scope thereof, it is to be understood that the invention is not limited to the specific embodiments.

I claim:

1. A comb having a back extending from one corner of the comb diagonally to the other corner, the center portion of the back having teeth projecting in both directions and the end portions having teeth projecting oppositely in one direction, ribs of cross section smaller than the back extending along the back at the bases of the teeth, the teeth being integral extensions of the ribs.

2. A comb according to claim 1 in which the ribs are subtended by grooves which extend along the sides of the back.

3. A comb according to claim 2 in which the back of the comb has a generally convex perimeter in cross section, the ribs being formed by grooves in the nature of concave fluting.

4. A comb according to claim 1 in which the teeth have elongated diamond shape and rounded edges when viewed in cross section, and which are wider at the groove than the thickness of the rib.

5. A comb according to claim 2 in which the bases of the teeth are wider than the ribs from which they spring and leave at least a portion of the fluting unobstructed.

6. A comb according to claim 5 in which the greatest width of the short axis of the fine teeth is about .034 inches, the greatest width of the short axis of the large teeth is about .054 inches, and the greatest thickness of the short axis of the back is slightly greater than the large axis of the teeth at the same point.

7. A comb according to claim 4 in which the ribs have smooth, convex, curved faces between the teeth.
